Specification for Design.

Patented Nov. 11, 1919.

Application filed May 17, 1919. Serial No. 297,969. Term of patent 14 years.

To all whom it may concern:

Be it known that I, JACOB LINDLEY, a citizen of the United States of America, and resident of Tiltonsville, county of Jefferson, and State of Ohio, have invented a new, original, and ornamental Design for Urinals, of which the following is a specification, reference being had to the accompanying drawings, in which—

The figure is a perspective view of a urinal, showing my new design.

Copies of this patent may be obtained for five cents each, by addressing the "Commissioner of Patents, Washington, D. C."

I claim:

The ornamental design for a urinal, as shown.

In testimony whereof I have hereunto affixed my signature in the presence of two subscribing witnesses.

JACOB LINDLEY.
